MANUALLY DRIVEN CASTING MACHINE

Webster I. Carpenter, Norfolk, Va.

Application May 31, 1934, Serial No. 728,453

9 Claims. (Cl. 22—65.1)

This invention relates to a centrifugal casting machine designed primarily for use in the making of metallic dental castings, but it is to be understood that a machine, in accordance with this invention may be employed in any connection for which it is found applicable, and has for its object to provide a machine of the class referred to, constructed in a manner as hereinafter set forth whereby the applied force thereto will initially create a lifting action upon a casting element carrying a body of molten metal for throwing the latter down into the mold on the first half of the first revolution of the machine and immediately following the throwing of the metal into the mold building up a centrifugal force sufficient to retain the metal in the mold during the second half of said first revolution and during successive revolutions of the machine until the metal has cooled sufficiently to retain shape.

Centrifugal force is a delayed force, it takes time to build it up and for that reason it is not dependable to force the metal in the mold while it is very hot. It is true that centrifugal force is used in some forms of casting machines to force the molten metal into the mold, but it is recognized that also, that the metal has slightly cooled before the centrifugal force has built up sufficiently to force the metal into the mold, and for this reason it is found that when using a specified size sprue opening to mold that the molten metal, having slightly cooled while awaiting for the centrifugal force to build up, does not flow as freely, thereby preventing as much molten metal flowing through the specified sprue opening as would be possible, could the molten metal be forced into the mold immediately while it is very hot, and in a very high state of fluidity. It is further recognized, that molten metal in a very high state of fluidity or while very hot, will adapt to the shape, and crevices of the mold more perfectly, than it is possible to do when it has slightly cooled, yet though, still in a fluid state, is not as mobile as a very hot freely flowing molten metal. It is the primary object of this invention to immediately on the start of the machine to throw very hot freely flowing molten metal into the mold to attain the advantage as aforesaid.

A further object of the invention is to provide a construction of casting machine whereby molten metal will be thrown immediately into a mold on the starting of the machine resulting in a more molten metal being forced into the mold through a specified size sprue opening than would be the case should the metal be allowed to slight-

ly cool. This has a practical value to the dentist, or the user of the machine. It means that the one using the machine does not have to use a large number of sprue openings to the mold to accommodate the passage of the molten metal, because the machine acts to throw the molten metal immediately into the mold while the metal is in a very fluid state.

A further object of the invention is to provide a centrifugal casting machine for throwing metal in a very fluid state into a mold, whereby the very hot fluid state metal will adapt itself to all nooks and crannies of the mold, thereby making a casting with sharp detail that is a perfect casting. It is a well known fact that when the molten metal has seriously cooled, that it does not, in a rather stiffened condition, flow to all nooks and crannies of the mold. Castings, therefore, have no detail, and the edges all are round, without sharp detail.

A further object of the invention is to provide a centrifugal casting machine which will permit of the metal, being heated in the end of the casting element, itself. This keeps the said element hot while the metal is being melted. When the metal is melted, the machine is started, the metal does not have to travel through the air from a crucible to the casting element and thereby cool off seriously, but it being already on the top of the casting element, when the machine starts, is thrown immediately into the mold through the sprue opening leading to the latter.

In the drawings:—

Figure 1 is a side elevation, partly in section of the centrifugal casting machine.

Figure 2 is a fragmentary view of the machine partly in longitudinal section.

Figure 3 is a detail sectional view illustrating the carrier or basket and casting element, and

Figure 4 is a view looking toward the inner face of the housing for the manually driven driving mechanism.

The machine includes a housing 5 formed of a semi-oval part 6 and a tubular part 7 extending upwardly from one end of the part 6. The latter has a front wall 8 and a rear wall 9 formed with an opening 10. The wall 8 has an opening 11. Arranged within the part 6 is a train of gearing 12 for rotating a sectional operating shaft 13 which extends from within the part 6 and up through and above the upper end of part 7. Only one of the gears of the train 12 is shown and which is designated at 14. The gear 14 is fixed to a rotatable drive shaft 15 therefor. The shaft 15 is journaled in and extends outwardly

through opening 11 from wall 8. The shaft 15 carries a crank handle 16 for manually rotating it.

Formed integral (Figure 4) with the upper portion of the outer face of wall 9 is a pair of spaced aligning clamping lugs 17, 18 disposed upon the same inclined plane. Integral with the lower portion of the outer face of wall 9 below and at a point between the lugs 17, 18 is an inclined apertured lug 19. The upper face of lug 19 is disposed in an incline plane parallel to the plane of the lower faces of lugs 17, 18. The aperture in lug 19 is designated 20 and has its wall threaded. A clamping screw 21 extends upwardly through lug 19 and threadedly engages with the wall of opening 20. The screw 21 at its upper end is formed with an enlarged part 22 to constitute an abutment which is disposed in a plane parallel to the plane of the inner faces of lugs 17, 18. The screw 21 coacts with the lugs 17, 18 for clamping housing 5 to support 23 and the inclined inner faces of the lugs 17, 18 in connection with the inclined abutment part 22 coact with the support 23 to dispose the shaft 13 at an inclination to the perpendicular, that is to say at 25 an obtuse angle with respect to drive shaft 15.

The shaft 13 is formed of a lower section 24 and an upper section 25. The section 24 at its upper end is bifurcated as at 26. The section 25 is enlarged at its lower end, as at 27 and formed 30 with a socket, as at 28 for receiving the bifurcated upper portion of section 24. The shaft sections 24, 25 are connected together so they will rotate in unison by a pin 29 which is secured to part 27 diametrically of the latter and extends 35 across and seats upon the bottom wall of the furcation 30. The depth of the furcation 30 is such that when shaft sections 24, 25 are coupled together the lower end of section 25 will be spaced from the top edge 31 of part 7 of housing 5. The 40 upper end of shaft 25 is formed with a sleeve 32 provided with internal threads 33. The sleeve 32 is disposed transversely of and at a slight upward inclination from one end to the other with respect to the axis of shaft 13. The length and 45 inner diameter of sleeve 32 is greater than that part of the shaft 13 below the sleeve.

Extending through and threadedly engaging with the sleeve 32 is a horizontally disposed hanger shaft 34 provided intermediate its ends with a group of threads 35 and at each end with a group of threads indicated at 36, 37. At the inner ends of the groups 36, 37 shaft 34 is formed with shoulders 38, 39 respectively. The shaft 34 is disposed at a slight upward inclination from one end to the other due to the pitch of sleeve 32. The shaft 34 is also disposed at an oblique angle with respect to the shaft 13. Each end edge of shaft 34 is formed with a concave recess indicated at 40, 41. Associated with each end of shaft 34 50 is a suspension member indicated at 42, 43. The member 42 consists of a stem 44 having its upper end formed with a spherical enlargement on ball 45 and its lower end reduced as at 46 and provided with an aperture 47. The member 43 consists of a stem 48 formed at its upper and lower ends with spherical enlargements or balls 49, 50 respectively. The enlargements 45, 49 are seated in the recesses 40, 41 respectively, and are coupled to shaft 34 by the internally threaded retaining collars 51, 52 respectively which threadedly engage with threads 36, 37 respectively and abut shoulders 38, 39 respectively and extend from the ends of shaft 34. The collars 51, 52 are formed at their outer ends with inwardly extending annular flanges 53, 54 respectively hav-

ing curved rear faces bearing against the enlargements 45, 49 respectively. The recess 41, enlargement 45 and sleeve 51 provides a universal joint connection between the suspension member 42 and shaft 34. The recess 41, enlargement 43 and sleeve 52 forms a universal joint connection between the suspension member 43 and shaft 34. The shaft 34 is revolved from shaft 13 to travel in a substantially disposed horizontal circular path arranged at a slight inclination with respect to a perpendicular line extending through the vertical median of the sleeve 32, whereby the ends of shaft 34 will alternately travel upwardly and downwardly while moving in the path of travel thereof.

There is associated with one end of shaft 34 a freely pivoting carrier or basket 55 for a casting element 56. The carrier 55 consists of a bottom plate 57, a pair of oppositely disposed suspension arms 58, 59 joined at their lower ends to diametrically opposed points of plate 57. The arms 58, 59, having their upper parts extended inwardly at an upward inclination as at 60, 61 respectively and then vertically as at 62, 63 respectively. The portions 62, 63 of arms 58, 59 are arranged in parallel spaced relation and apertured as at 64. Secured to the inner faces of the arms 58, 59 between the transverse medians thereof and their lower ends is an annulus 65 for removably supporting a removable annular balance 66. The lower end 46 is disposed between the portions 62, 63 of arms 58, 59 respectively and with its opening 47 aligning with the apertures 64. Extending through opening 47 and apertures 64 is a pivot bolt 67 carrying a retaining nut 68. The pivot 67 is disposed at right angles to the axis of shaft 34.

There is associated with the other end of shaft 34 a freely movable counterbalance 69 consisting of a weight 70 having a reduced end portion 71 formed within its edge 72 with a concave recess 73. The weight 70 is closely encompassed throughout, with the exception of its edges 72 by a casing 74 extended from said edge. Casing 74 is peripherally threaded as at 75 and is formed of any suitable metallic material possessing a characteristic to reduce the indenting thereof to a minimum. The enlargement 50 is seated in the recess 73. Threadedly engaging with the casing 74 is a flanged retaining member 76 formed with an opening 77 for a passage of the part of the enlargement 50. The member 76 couples the enlargement 50 to the counterbalance 69 and forms in connection with recess 73 and said enlargement a universal joint connection between member 43 and counterbalance 69.

With reference to Figure 3 the casting element 56 is shown as consisting of a ring 78, an investment 79 having a molding chamber 80 and a sprue opening 81 leading to the latter. One end of the investment is formed with a recess 82 to receive the metallic body 83 which is to be melted. The recess is arranged at the base of an opening 84 having its wall terraced as at 85. The outer end of the sprue opening 84 communicates with the recess 82.

The shaft 34 is shiftable relative to sleeve 32 for adjusting it to balanced position and when adjusted one end thereof is moved away from and its other end moved towards the center of gravity without it being necessary to adjust the counterbalance lengthwise of said shaft.

The counterbalance 69 is loosely suspended from one end of shaft 34 so as to allow freedom of movement of the latter for a quick start. This 75

is necessary in a manually controlled machine, since it is the natural way for an operator to pull lightly on the handle of the machine when first starting it, and gradually increasing the pull of the handle until he has speeded the machine up to the desired speed, at which time he lessens the pull on the handle, thereby maintaining the machine at the desired speed only. The machine is constructed to function properly as to end result, 10 by not weighting too heavily the shaft 34 thereby preventing the machine from starting at the desired speed.

The machine permits of the metal being heated in one end of the casting element itself by a blow 15 pipe, and this keeps the said element hot while the metal is being melted. When the metal has melted, the machine is started and the molten metal travels immediately into the molding chamber through the sprue opening. The construction of the machine will give a lift action on 20 the starting thereof, before any centrifugal force has had time to build up and such action throws the very hot molten metal immediately down into the molding chamber on the first half turn of 25 the first turn of shaft 34. By this time the centrifugal force has built up sufficiently to retain the molten metal in the molding chamber during the second one half turn of the shaft 34, and for all successive turns of said shaft, until the metal has 30 cooled sufficiently to retain shape. The lifting action attained on the starting of the machine is due to the inclination of the operating shaft. The arranging of sleeve 32 in the manner as 35 shown prevents the carrier or counterbalance carried by shaft 34 hitting the support 23, the blow pipe on the latter or other objects on the support during the revolving of shaft 34, and which would not be the case if the ends of sleeve 32 were parallel to the axis of shaft 13.

When the machine is operated, the shaft 34 sweeps out two conical paths with the apices of the cones adjacent. The axes of the two cones being common to each other and being one and the same as the axis of the shaft 13. Upon 40 initially starting the machine, the shaft 34 not only starts to course in a circle, but as the shaft 34 travels in a slightly upward direction, the carrier 55 swings outwardly and the shaft 34 tends to lift the carrier 55 until its long axis approaches 45 a point approximately at right angle to the axis of shaft 34, and therefore the centrifugal force does not whip the carrier up to position as the machine speeds up. During the aforesaid outward and lifting action applied to the carrier 55, the 50 latter at the same time being carried in a circular path, the axis of which is parallel and one and the same as the axis of shaft 13. The axis of shaft 13 is permanently inclined to the vertical. No two points of the shaft 34 travel in the same 55 path, but each individual point of shaft 34 travels in a circular path, the axis of which is the axis of shaft 13.

What I claim is:

1. In a centrifugal casting machine a manually 65 driven upstanding operating shaft permanently inclined with respect to the vertical, a hanger shaft disposed at an oblique angle to said operating shaft and having all of its points travelling in circular paths and with no two of said points 70 being in the same plane, said shafts having coacting interengaging means for adjustably mounting the hanger shaft on the upper end of the operating shaft and for permanently maintaining the hanger shaft at an oblique angle to the operating 75 shaft, said hanger shaft projecting through and

extending from that part of said means on said operating shaft, a pair of oppositely disposed suspension members, means attached to the ends of the hanger shaft and coacting with parts of the latter and with parts of said members for forming universal connections between the upper ends of said members and the ends of the hanger shaft, a casting element carrier, means for pivotally connecting the upper end of the carrier to the lower end of one of said members, a counterbalance, and means connected to the counterbalance and coacting with a part of the latter and with a part of said other member for forming a universal connection between the lower end of the said other member and said counterbalance. 10

2. In a centrifugal casting machine a manually driven upstanding operating shaft permanently inclined with respect to the vertical, a hanger shaft disposed at an oblique angle to said operating shaft and having all of its points travelling 20 in circular paths and with no two of said points being in the same plane, said shafts having coacting interengaging means for adjustably mounting the hanger shaft on the upper end of the operating shaft and for permanently maintaining the hanger shaft at an oblique angle to the operating shaft, said hanger shaft projecting through and extending from that part of said means on said operating shaft, a pair of oppositely disposed suspension members, means attached 30 to the ends of the hanger shaft and coacting with parts of the latter and with parts of said members for forming universal connection between the upper ends of said members and the ends of the hanger shaft, a casting element carrier, means for pivotally connecting the upper end of the carrier to the lower end of one of said members, a counterbalance, and means connected to the counterbalance and coacting with a part of the latter and with a part of said other member for forming a universal connection between the lower end of the said other member and said counterbalance. 35

3. In a centrifugal casting machine a manually driven upstanding operating shaft permanently 40 inclined with respect to the vertical, a hanger shaft disposed at an oblique angle to said operating shaft and having all of its points travelling in circular paths and with no two of said points being in the same plane, said shafts having coacting interengaging means for adjustably mounting the hanger shaft on the upper end of the operating shaft and for permanently maintaining the hanger shaft at an oblique angle to the operating shaft, said hanger shaft projecting through and extending from that part of said means on said operating shaft, a pair of oppositely disposed suspension members, means attached 45 to the ends of the hanger shaft and coacting with parts of the latter and with parts of said members for forming universal connection between the upper ends of said members and the ends of the hanger shaft, a casting element carrier, means for pivotally connecting the upper end of the carrier to the lower end of one of said members, a counterbalance, and means connected to the counterbalance and coacting with a part of the latter and with a part of said other member for forming a universal connection between the lower end of the said other member and said counterbalance. 50

4. In a centrifugal casting machine a manually driven upstanding operating shaft permanently 55 inclined with respect to the vertical, a hanger shaft disposed at an oblique angle to said operating shaft and having all of its points travelling in circular paths and with no two of said points being in the same plane, said shafts having coacting interengaging means for adjustably mounting the hanger shaft on the upper end of the operating shaft and for permanently maintaining the hanger shaft at an oblique angle to the operating 60 shaft, said hanger shaft projecting through and extending from that part of said means on said operating shaft, a pair of oppositely disposed suspension members, means attached to the ends of the hanger shaft and coacting with parts of the latter and with parts of said members for forming universal connections between the upper ends of said members and the ends of the hanger shaft, a casting element carrier, means for pivotally connecting the upper end of the carrier to the lower end of one of said members, a counterbalance, and means connected to the counterbalance and coacting with a part of the latter and with a part of said other member for forming a universal connection between the lower end of the said other member and said 65 counterbalance. 70

5. In a centrifugal casting machine a manually driven upstanding operating shaft permanently inclined with respect to the vertical, a hanger shaft disposed at an oblique angle to said operating shaft and having all of its points travelling in circular paths and with no two of said points being in the same plane, said shafts having coacting interengaging means for adjustably mounting the hanger shaft on the upper end of the operating shaft and for permanently maintaining the hanger shaft at an oblique angle to the operating shaft, said hanger shaft projecting through and extending from that part of said means on said operating shaft, a pair of oppositely disposed suspension members, means attached to the ends of the hanger shaft and coacting with parts of the latter and with parts of said members for forming universal connections between the upper ends of said members and the ends of the hanger shaft, a casting element carrier, means for pivotally connecting the upper end of the carrier to the lower end of one of said members, a counterbalance, and means connected to the counterbalance and coacting with a part of the latter and with a part of said other member for forming a universal connection between the lower end of the said other member and said counterbalance. 75

counterbalance, that part of said mounting means on said operating shaft being arranged at the upper end of and disposed at an angle to the axis of such shaft and extending at an inclination from one of its ends to the other.

4. In a centrifugal casting machine a manually driven upstanding operating shaft permanently inclined with respect to the vertical, a hanger shaft disposed at an oblique angle to said operating shaft and having all of its points travelling in circular paths and with no two of said points being in the same plane, said shafts having coacting interengaging means for adjustably mounting the hanger shaft on the upper end of the operating shaft and for permanently maintaining the hanger shaft at an oblique angle to the operating shaft, said hanger shaft projecting through and extending from that part of said means on said operating shaft, a pair of oppositely disposed suspension members, means attached to the ends of the hanger shaft and coacting with parts of the latter and with parts of said members for forming universal connections between the upper ends of said members and the ends of the hanger shaft, a casting element carrier, means for pivotally connecting the upper end of the carrier to the lower end of one of said members, a counterbalance, and means connected to the counterbalance and coacting with a part of the latter and with a part of said other member for forming a universal connection between the lower end of the said other member and said counterbalance, and a driving structure for and connected to said operating shaft, said structure having means for clamping it to and at an inclination with respect to a support therefor for maintaining said driving shaft at an inclination to the vertical, that part of said mounting means on said operating shaft being arranged at the upper end of and disposed at an angle to the axis of such shaft and extending at an inclination from one of its ends to the other.

5. In a centrifugal casting machine, an upstanding operating shaft permanently inclined with respect to the vertical, a hanger shaft disposed at an oblique angle to said operating shaft and having all of its points travelling in circular paths and with no two of said points being in the same plane, means for connecting the hanger shaft intermediate its ends to the upper end of the operating shaft and for permanently maintaining the hanger shaft in oblique angled relation with respect to the operating shaft, said hanger shaft being formed at each end edge with a recess, a pair of oppositely disposed suspension members each having a globular enlargement at one end seating in a recess, means for loosely connecting said enlargement in said recess and in extended relation with respect to the ends of said hanger shaft, a casting element carrier, means for pivotally connecting one end of said carrier to the other end of one of said members, a counterbalance having a recess at one end, the other of said members having its other end formed with a globular enlargement seating in the recess of said counterbalance, means engaging with said counterbalance for loosely connecting in the latter the globular enlargement on the said other end of the said other suspension member, and a driving structure for said operating shaft.

6. In a centrifugal casting machine, an upstanding operating shaft permanently inclined

with respect to the vertical, a hanger shaft disposed at an oblique angle to said operating shaft and having all of its points travelling in circular paths and with no two of said points being in the same plane, means for connecting the hanger shaft intermediate its end to the upper end of the operating shaft and for permanently maintaining the hanger shaft in oblique angled relation with respect to the operating shaft, said hanger shaft being formed at each end edge with a recess, a pair of oppositely disposed suspension members each having a globular enlargement at one end seating in a recess, means for loosely connecting said enlargement in said recess and in extended relation with respect to the ends of said hanger shaft, a casting element carrier, means for pivotally connecting one end of said carrier to the other end of one of said members, a counterbalance having a recess at one end, the other of said members having its other end formed with a globular enlargement seating in the recess of said counterbalance, means engaging with said counterbalance for loosely connecting in the latter the globular enlargement on the said other end of the said other suspension member, and a driving structure for said operating shaft, said driving structure being provided with means for clamping it to a support and for maintaining said operating shaft at an inclination with respect to the vertical.

7. In a centrifugal casting machine, an upstanding manually actuated operating shaft permanently disposed at an inclination to the vertical, a hanger shaft, a pivoted mold carrier universally movably suspended from one end of said hanger shaft, a counterbalance universally movably suspended from the other end of said hanger shaft, and means for connecting said hanger shaft intermediate its ends to the upper end of and for disposing the hanger shaft at an oblique angle to said operating shaft, said means providing for the revolving of the carrier in circular paths by said operating shaft.

8. In a centrifugal casting machine, an upstanding operating shaft permanently inclined to the vertical, a horizontal hanger shaft for revolving in circular paths, operated by said operating shaft and permanently disposed at an oblique angle to the operating shaft, a mold carrier, a counterbalance, means for loosely suspending the mold carrier from one end of the hanger shaft, means for loosely suspending the counterbalance from the other end of said hanger shaft, and means for connecting the hanger shaft intermediate its ends to the upper end of the operating shaft and for permanently maintaining the hanger shaft at an oblique angle to the operating shaft.

9. In a centrifugal casting machine, a revolvable hanger shaft, a counterweight, a mold carrier, a combined connection and suspension structure for said counterweight having means at one end for universally coupling one end thereof to one end of said shaft and means at its other end for universally coupling the other end thereof to said counterweight, and combined connection and suspension structure for said carrier having means at one end for universally coupling one end thereof to the other end of said shaft and means at its other end for pivotally connecting the other end thereof to said carrier.
